UNITED STATES PATENT OFFICE.

ARTHUR A. OSWALD, OF EAST ORANGE, NEW JERSEY, ASSIGNOR TO WESTERN ELECTRIC COMPANY, INCORPORATED, OF NEW YORK, N. Y., A CORPORATION OF NEW YORK.

HIGH-POWER RADIOTELEPHONY.

Application filed March 20, 1924. Serial No. 700,557.

To all whom it may concern:

Be it known that I, ARTHUR A. OSWALD, a citizen of the United States of America, residing at East Orange, in the county of 5 Essex and State of New Jersey, have invented certain new and useful Improvements in High-Power Radiotelephony, of which the following is a full, clear, concise, and exact description.

10 This invention relates to radio telephone transmission at frequencies adapted for long distance communication.

Hitherto, radio telephone communication has been largely accomplished by transmission 15 at wave lengths of 100,000 cycles and upward and at relatively low powers. For long distance communication, it is deemed advisable for practical reasons to operate at frequencies below 100,000 cycles. In particular, in a series of experimental tests, in 20 which the methods and apparatus of the present invention were used, a frequency band centering around 57,000 cycles has been used.

25 Ordinary antennæ usually have a transmission band of insufficient width to radiate a band of frequencies of the width of the speech band and extending, for example, from 55,750 to 58,250 cycles. A certain antenna which was used had a transmission band of only 1100 cycles. It has been found that such an antenna can be associated with 30 vacuum tube apparatus in such a manner as to provide an effective input-response frequency characteristic substantially uniform over a band width of 2500 cycles without 35 greatly reducing the operating efficiency of the vacuum tubes. It has developed that the problems involved in radio transmission 40 of a band of frequencies of 2,000 cycles or more at high efficiency are considerably more difficult than the problems involved in radiating a similar amount of energy in a band of frequencies so narrow as to constitute 45 practically a single frequency, as in radio telegraph transmission at ordinary speeds. The solution of certain of these problems is effected by the apparatus and methods herein described, but the invention does not inhere 50 in any particular theory or explanation of supposed reasons for the results obtained. Hence, any theory or explanation advanced herein is to be considered as an explanation of the invention and not as a limitation 55 thereof.

One object of the invention is to provide a method of widening the transmission band of an antenna circuit by employing vacuum tubes in combination therewith and in connection with a coupling circuit so designed 60 that the tubes assist in widening the band.

A feature of the invention consists in a circuit so designed that the tubes work into an impedance which increases in value as 65 the edges of the band are approached.

Further objects are to amplify to high power and transmit a radio wave of speech band width. In general, the widening of the transmitted band of frequencies in this 70 manner results in some decrease in efficiency as compared with the efficiency which might be secured with the same tubes in transmitting a current of a single frequency. The cause of this is that the application of the method herein described results in there being impressed on the anode circuit of the tubes increased electromotive forces. In the 75 usual practical case, the application of the method is restricted by the maximum voltage which the tubes will stand. This requires 80 that, if the tubes are operating at maximum voltage prior to the application of the method, then upon the application of the method, the voltage resulting from the transmission of waves in the middle of the transmitted frequency band must be reduced.

A further object is to improve circuits for coupling power tubes to an antenna circuit.

In carrying out the invention in practice, use has been made of a group of approximately twenty water-cooled anode power tubes rated at 10 kilowatts each and supplied with space current at a tension of approximately 10,000 volts. These tubes constitute the final stage of a power amplifier. 90 A tuned circuit couples the tubes to the aerial circuit which consists of a multiple directive antenna of a well-known type. Such antennæ are described in articles by 95 Alexanderson and Bucher in the General Electric Review for October 1920 and an article by Alexanderson, Reoch and Taylor in the A. I. E. E. Proceedings for July 1923. Further details of the vacuum tube apparatus and circuits will be given hereinafter. 100

In operating, it has been found that not only can a fairly flat transmission characteristic be obtained but, if desired, portions of the transmitted wave band near the edges thereof can be so effectively converted into 110

the electromagnetic radiation that unequal attenuation of speech input apparatus, such as a long telephone line can be wholly or partly compensated for.

5 The invention will be described in greater detail in connection with the accompanying drawings.

Fig. 1 is a partly diagrammatic and partly schematic illustration of the circuit employed.

Fig. 1^a is a more detailed disclosure of a coupling circuit.

Fig. 2 is a graph illustrating the widening of the transmission band.

15 Fig. 3 is a graph of the variation of the impedance of the power tube anode circuit with frequency.

Referring to Fig. 1, the source of speech frequency waves 1 is connected to the input circuit of modulator 2 which is supplied with high frequency carrier waves from source 3. Filter 4 selects one side band from the resultant modulated wave. The apparatus 1, 2, 3, 4 indicate any desired type of combination of elements suitable for producing a side band of speech frequency width. The side band thus produced is amplified in any desired number of stages by amplifiers 5, to the output circuit of which is connected a power tube amplifying system 6. The power tube amplifier 6 has its output circuit connected to a tuned circuit 7 which is in turn coupled to a multiple tuned antenna 8. The system 6 is supplied with grid voltage of a tension of 250 to 350 volts from a source 9 through a suitable filter 10. The cathodes are heated from a 60 cycle or other commercial source of current 11. Anode current is supplied by a source 12 having a terminal voltage of 40 7,000 to 11,000 volts in accordance with the particular adjustment and power.

In order to couple the power amplifier system 6 with the aerial system 8, the coupling circuit 7 is provided. A capacity 13 functioning as a stopping condenser prevents short-circuiting of the source 12. The coupling circuit 7 comprises a variable inductance 15, a coupling inductance 16, and capacities 14 and 20. The coupling inductance 16 is coupled to the inductance coil 17 which is located in the down lead of the antenna circuit.

The antenna circuit comprises a plurality of sections 18 connected to each other with inductance coils 19 extending from the points of connection to ground.

Some of the requirements for the system are that, having given an amplifier capable of delivering a certain amount of high frequency power and an antenna with certain characteristics, the intermediate circuit must be designed to satisfy the impedance requirements both of the power tubes and of the antenna. A second condition is that the power at all of the frequencies in the band

must receive substantially the same amplification in passing through the system to the antenna. In order to prevent interference, currents of harmonic frequencies must not be allowed to flow in the antenna. At the frequency used the multiple resistance of the antenna is approximately .75 ohms. The radiation resistance, taking account of the directive effect, is little more than .3 ohms. The radiation efficiency is therefore more than 40%. Such a low antenna resistance is of itself desirable, but it results in a narrow resonance characteristic effect which for telephony, leads to certain complications. The band width is here arbitrarily taken as the difference between the two frequencies for which the impedance of the tuned antenna circuit is double the minimum value. It is particularly desirable to transmit a wider band than this where the system is used with standard microphones, receivers and relative long-line connections at each end.

The electrical design procedure consists of two steps; first, a preliminary determination of certain constants on the basis of a single frequency, and second, an examination of the frequency-impedance characteristic throughout the band for the purpose of modifying the constants so as to obtain the most practical input-response-frequency characteristic for the amplifier system.

When properly adjusted it has been found that the output impedance may have two peaks with a relatively low point approximately half-way between, as shown in Fig. 3 which is not drawn to scale but is intended to show the general shape of the impedance-frequency characteristic. At 57 kilocycles the antenna introduces only resistance into the primary circuit. At lower frequencies positive reactance is introduced and at a somewhat lower point about 55.7 kilocycles the impedance passes through a maximum. For frequencies above 57 kilocycles capacity reactance is added to the inductive branch of the tuned circuit 7 making it anti-resonant at the frequency around 58.3 kilocycles. Another important feature is that the power factor is approximately unity at three different frequencies which occur at the middle and near the edges of the band. Furthermore, the impedances at the points A, B and C (Fig. 3) are not in any fixed relation but may be adjusted with respect to each other by adjustments of the circuit. In particular the impedances at the points B and C are capable of considerable regulation so that one peak may be considerably higher than the other if desired.

A characteristic feature of the invention, therefore, is that at frequencies near the edges of the transmitted band at which it is difficult to transfer energy into the antenna, the tubes are caused to work into an increased impedance. This

may be accomplished by proper proportioning of the electrical constants of the circuit elements shown in Fig. 1. This proportioning may be arrived at by computation or by 5 purely empirical methods.

Assuming that a constant voltage of varying frequency is applied to the grid circuit of the power amplifier and that the impedance of the tubes is zero, we would be 10 applying to the output circuit a constant voltage equal to μ times the alternating grid voltage, where μ is the amplification constant of tube. The antenna current characteristic would not differ very much from 15 the resonance curve of the antenna. But when account is taken of the fact that the impedance of the tubes is finite, we find that the same potential is not applied to the output circuit for all frequencies but is greatest 20 for frequencies for which the output impedance is greatest. Hence, there is a tendency to depress the antenna current characteristic at points of low output impedance. The effective band width may thus be made 25 several times as great as the resonance band of the antenna. The adjustment finally adopted should be one for which the efficiency of the amplifier is satisfactory.

In the application of this invention there 30 must be taken into account the fact that vacuum tube constants, and, in particular, the plate circuit impedance of a vacuum tube are not the same when large voltages 35 are impressed upon the grid circuit and the combination of high anode potential and high negative grid potential is employed as when small voltages are impressed upon the grid circuit and smaller anode potentials and grid polarizing potentials are employed. 40 When power tubes are employed under conditions selected with a view to obtaining high efficiencies, the effective internal tube impedance normally of the order of 5,000 ohms per tube with a particular type of 45 tube may be greatly increased.

The advantage of widening the input-response frequency characteristic is accompanied by a certain necessary disadvantage which is, namely, a diminished factor of 50 safety. With increase of output impedance there is a corresponding, although not proportional, increase in the alternating component of the anode potential. Consequently, the anode may become negative by a 55 value which may be as large as one-half the voltage of the direct current supply. There is no objection to this under ordinary circumstances, but in one-half of the cycle, since the wave is symmetrical, the anode potential 60 is of the order of two and one-half times the voltage supply. Hence, if the same factor of safety is to be maintained, a decreased rating for the power tubes must follow.

65 From the foregoing, it follows that radio telephone transmission may be accomplished

upon an antenna with a narrow resonance characteristic indicated by the curve d in Fig. 2 with a band width of 1,100 cycles or less with a resultant input voltage-response characteristic sufficiently uniform over a band of 2,500 cycles or more to permit of reasonably efficient transmission with a minimum of distortion. It has been, in fact, found that an antenna with a band width of 600 cycles could be effectively used. 70

Consideration must be given to the large increase of harmonics which results when the anode potential assumes negative values during part of the cycle. These currents of harmonic frequencies must be kept out of 75 the antenna. For high efficiencies it is considered desirable that the first three or four multiple frequency components pass through the condenser 14. The higher harmonics and particularly those which occur within the 80 broadcasting range at present employed, are disposed of by a special shunt arrangement to be described in connection with Fig. 1^a.

In Fig. 1^a a circuit 7 is illustrated in greater detail. The capacity 13 as employed in practice consists of a large bank of condensers arranged in a multiple-series combination. In order to equalize the direct potential component on these condensers, each 85 parallel group is shunted by high resistance, 90 since otherwise the result of small current leaks would be to impress upon the highest resistance parallel group a disproportionately large part of the direct potential applied 95 to the plate circuits. In consequence of placing resistances 21 around the condensers 13' it becomes necessary to utilize some 100 means for preventing the condensers 20 from receiving the entire 10,000 volts of the plate current supply generator 12. This 105 may be done by connecting similar high but lower resistance 22 around the condensers 20 or, if desired, by connecting a high impedance choke coil 23 from the right hand terminal of the condensers 13' to ground by 110 means of a switch 24. The coupling inductance 16 is shunted by a resistance 25 in series with a condenser 26. The impedance of the capacity 26 is such that it has little effect 115 at the operating frequency or the lower harmonics, but at the higher harmonic frequencies which fall within the broadcasting range where little interference can be tolerated, currents are shunted through the resistance 25 and 26 and thus diverted from 120 the aerial circuit.

The novel features believed to be inherent in the invention are set forth in the appended claims.

What is claimed is:

1. The method which comprises transmitting a band of frequencies of a total frequency range of the order of 2000 cycles through an antenna having a resonance characteristic materially narrower than 2000 125 130

cycles with a substantially uniform effectiveness over the entire frequency range of the band.

2. A system comprising a thermionic discharge device having a space discharge circuit connected to a radiating antenna by means of a tuned coupling circuit in combination with a negatively polarized control element in said space discharge tube, and an input means of sufficient power to cause said element to become positive at times.

3. The method of widening the transmission band of an antenna having vacuum tube repeaters feeding into the antenna, which consists in operating the tubes in such a manner that they assist in widening the band.

4. A radio transmission circuit for transmitting by means of an antenna a band of frequencies relatively wide as compared with the width of the resonance characteristic of the antenna which comprises a vacuum tube and a circuit coupled between the tube and the antenna, said circuit being so designed that the tube works into an impedance which increases in value as the edges of the band are approached.

5. A radio telephone transmission system comprising apparatus and circuit arrangements for producing a band of high frequency waves representing speech, a space discharge amplifier having a grid-cathode input circuit and an anode-cathode output circuit for amplifying the energy of the waves of said band, an adjustable tuned circuit connected to the anode-cathode circuit of said amplifier, and a multiple tuned antenna coupled to said adjustable circuit, the impedances of said adjustable circuit, of said antenna and of said anode-cathode path being so proportioned as to transmit waves at the edge of the band of frequencies with an effectiveness equal to or greater than the transmission at the middle of said band.

6. In combination, a source of high voltage, a stopping condenser connected between said source and a coupling circuit, said stopping condenser comprising capacity elements shunted by resistance to prevent the breakdown of the capacity elements, a capacity in said coupling circuit which is subjected to the voltage of said source as a result of leakage current through said resistance, said

capacity in said coupling circuit comprising capacity elements in series relation shunted by resistance.

7. A circuit for preventing harmonics from reaching a radiating antenna which comprises a high frequency transformer for transferring energy to said antenna, and a resistance and a condenser in series shunted across the primary of said transformer, the impedance of said resistance and condenser combination being high at the operating frequency and low at the frequencies of waves to be excluded from said antenna.

8. The method of widening the transmission characteristic of an amplifier delivering power to a tuned load circuit, which consists in coupling a primary circuit with said load circuit thereby introducing impedance into said primary circuit, said primary circuit being tuned to a frequency of the same order as said load circuit, said primary circuit being coupled with the output circuit of said amplifier in such a way that a variation of frequency tending to produce a decrease in the resistance of said primary circuit including that introduced due to said load circuit results in an increase in the impedance into which said amplifier works.

9. A transmission system comprising a load circuit, a repeater constituting a source for supplying a relatively wide band of frequencies to said load circuit, said load circuit comprising elements electrically selective of a portion of the frequencies of the band in the central zone thereof, in combination with a coupling circuit interposed between said source and said load circuit, said coupling circuit consisting of impedance elements having their impedances so proportioned and so related to the impedance of said source and of said load circuit that the impedance of said coupling circuit including the impedance introduced from said load circuit as viewed from said source is of considerably greater numerical value at the edge frequencies of said band than in the central zone thereof, whereby greater uniformity of transmission of waves of frequencies within said band is attained.

In witness whereof, I hereunto subscribe my name this 7th day of March A. D., 1924.

ARTHUR A. OSWALD.
